Detroit, Mich.

Application November 8, 1935, Serial No. 48,801

7 Claims. (Cl. 229—16)

This invention relates to containers and particularly cigarette cases.

An object of the invention is to form a cigarette case or like container from a single blank of sheet material, by extending tongues from the lateral and bottom edges of a rectangular portion of the blank forming one of the container walls, bending the lateral tongues to form a pair of opposed side walls and further bending them to form outer members of a fourth wall, and bending the bottom tongue to form a bottom member for the container and further bending it to form an inner member of the fourth wall, a common means being employed to connect the outer members of the fourth wall to each other and to the inner member.

Another object is to form said lateral tongues with a pair of relatively small tongues integrally projecting from the lower edges of said opposed side walls and bent toward each other to form inner bottom members, and to interconnect such members.

Another object is to give the free edges of the first-mentioned or outer bottom member a reentrant form assuring them a clearance from the walls or contents of a pocket wherein the case may be carried.

A further object is to additionally form said blank with a tongue at its upper edge forming a cover for the container and a flap for holding the cover closed, and to exteriorly mount a keeper strap on the fourth wall to receive said flap.

Further objects are to conceal beneath said keeper strap the connections between the inner and outer members of the fourth wall and to utilize such connections to hold said strap in place.

These and various other objects the invention attains by the construction hereinafter described and illustrated in the accompanying drawing, wherein:

Fig. 1 is a view of the blank from which the described cigarette case may be formed.

Fig. 2 is a perspective view of the case with its cover in raised position.

Fig. 3 is a similar view of the case showing the cover engaging its keeper.

Fig. 4 is a cross sectional view of the case taken upon the line 4—4 of Fig. 2.

Fig. 5 is a bottom view of the case.

Fig. 6 is a vertical sectional view of the bottom portion of the case taken on the line 6—6 of Fig. 4.

In these views the reference character 1 designates a rectangular center portion of a blank formed of leather or other suitable flexible sheet

material and integrally provided with a pair of tongues projecting oppositely laterally from said center portion and also with upwardly and downwardly projecting tongues. The lateral tongues are bent at their junctures 2 with the wall 1 to form a pair of opposed side walls 3 and are further bent at 4 to form a pair of members 5 projecting toward each other and abutting as indicated at 6 to form outer members of the fourth wall of the case.

The lower tongue is bent at 7 to form an outer bottom member 8 of the case and is again bent at 9 to extend snugly upward between the side walls 3 and form an inner member 10 of said fourth wall. The walls 3 at their lower edges are integrally formed with a pair of relatively small tongues 11 bent to extend toward each other to form inner bottom members abutting at 12, centrally above the outer bottom member 8. A pair of staples or other suitable fastenings 13 interconnect the abutting ends of the tongues 11, as best appears in Figs. 4 and 6, being concealed by the member 8. Preferably the latter member has its opposite free edges 14 of a reentrant form that will assure such edges against catching on the walls or contents of any pocket in which the case may be carried.

Extending exteriorly across the fourth wall of the case is a keeper strap 15 having its end portions passed through suitable slits in the members 5 and bent toward each other between such members and the member 10. A plurality of staples 16 serve to connect the inner and outer members of the fourth wall to each other and to the end portions of said strap, and at least one of said staples serves also to interconnect the members 5 and to also interconnect the strap ends.

The upper tongue is adapted to be bent at 17 to form a cover panel 18 for the case and to be further bent at 19 to form a flap 20 insertable under the keeper strap.

It is a feature of the described construction that the fastenings, interconnecting the inner and outer members of the fourth wall and further fastening the keeper strap to such members, are entirely concealed beneath the exterior portion of such strap. It is also a feature that the fasteners 13 interconnecting the complementary inner members 11 of the container bottom are entirely concealed by the outer bottom member 8.

Another important feature of the construction is utilization of the members 11 to close the gaps which might otherwise occur between the member 8 and the walls 3 of the case.

Thus use of inner and outer members to form

the keeper-mounting wall and the bottom of the case adds materially to its strength, and the fact that all four walls and the top and bottom of the case are formed from a single blank simplifies manufacture and reduces its cost.

The invention is presented as including all such modifications and changes as come within the scope of the following claims.

What we claim is:

10. 1. A container formed of flexible sheet material and comprising a substantially rectangular wall integrally formed with a pair of tongues projecting from its lateral edges, and with an upper and a lower tongue at its other edges, the lateral 15 tongues being bent at their junctures with the first-mentioned wall to form a pair of opposed walls and being further bent toward each other to form outer members of a fourth wall, opposed to the first-mentioned wall, the lower tongue being bent at its juncture with the first-mentioned wall to form a bottom member of the container and being again bent to extend upwardly between and adjacent to said opposed walls to form an inner member of the fourth wall, the upper 20 tongue being bent at its juncture with the first-mentioned wall to form a cover for the container, and being further bent to form a securing flap exteriorly engageable with the fourth wall, a keeper for such flap exteriorly carried by the 25 fourth wall, and means concealed by the keeper for securing together the outer members of the fourth wall.

2. A container formed of flexible sheet material comprising a substantially rectangular wall 30 integrally formed with a pair of tongues projecting from its lateral edges and further formed with an upper and a lower tongue integrally projecting from its upper and lower edges, the laterally projecting tongues being bent at their 35 junctures with the first-mentioned wall to form a pair of opposed walls and being further bent toward each other to form outer members of a fourth wall, the lower tongue being bent at its juncture with the first-mentioned wall to form a bottom 40 for the container and being again bent to extend upwardly between said opposed walls to form an inner member of the fourth wall, a keeper strap exteriorly extended upon the fourth wall and having end portions extending through 45 the outer members of the fourth wall and bent toward each other between said inner and outer members, and a common means for securing the inner and outer members of the fourth wall to each other and to the end portions of the keeper 50 strap, the upper tongue being bent at its juncture with the first-mentioned wall to form a cover for the container and being further bent to form a flap engageable with said keeper strap.

3. A container formed of flexible sheet material comprising a substantially rectangular wall 55 integrally formed with a pair of tongues projecting from its lateral edges and further formed with an upper and a lower tongue integrally projecting from its upper and lower edges, the laterally projecting tongues being bent at their 60 junctures with the first-mentioned wall to form a pair of opposed walls and being further bent toward each other to form outer members of a fourth wall, the lower tongue being bent at its juncture with the first-mentioned wall to form a bottom 65 for the container and being again bent to extend upwardly between said opposed walls to form an inner member of the fourth wall, a keeper strap exteriorly extended upon the fourth wall 70 and having end portions extending through the

outer members of the fourth wall and bent toward each other between said inner and outer members, and means for interconnecting said end portions, the upper tongue being bent at its juncture with the first-mentioned wall to form 5 a cover for the container and being further bent to form a flap engageable with said keeper strap.

4. A container formed of flexible sheet material comprising a substantially rectangular wall 10 integrally formed with a pair of tongues projecting from its lateral edges and further formed with an upper and a lower tongue integrally projecting from its upper and lower edges, the laterally projecting tongues being bent at their junctures with the first-mentioned wall to form 15 a pair of opposed walls and being further bent toward each other to form outer members of a fourth wall, the lower tongue being bent at its juncture with the first-mentioned wall to form a bottom for the container and being again bent 20 to extend upwardly between said opposed walls to form an inner member of the fourth wall, a keeper strap exteriorly extended upon the fourth wall and having end portions engaged between said inner and outer members, and a common 25 means for securing the inner and outer members of the fourth wall to each other and to the end portions of the keeper strap, the upper tongue being bent at its juncture with the first-mentioned wall to form a cover for the container 30 and being further bent to form a flap engageable with said keeper strap.

5. A container formed of flexible sheet material comprising a substantially rectangular wall 35 integrally formed with a pair of tongues projecting from its lateral edges and further formed with an upper and a lower tongue integrally projecting from its upper and lower edges, the laterally projecting tongues being bent at their 40 junctures with the first-mentioned wall to form a pair of opposed walls and being further bent toward each other to form members of a fourth wall, the lower tongue being bent at its juncture with the first-mentioned wall to form a bottom for the container and being again bent to extend 45 upwardly to form another member of the fourth wall, whereby the fourth wall is of double thickness, a keeper strap exteriorly extended upon the fourth wall and having end portions extending through the outer thickness of the fourth wall 50 and bent toward each other between the two thicknesses, and a common means for securing the two thicknesses of the fourth wall to each other and to the end portions of the keeper strap, the upper tongue being bent at its juncture with 55 the first-mentioned wall to form a cover for the container and being further bent to form a flap engageable with said keeper strap.

6. A container formed of flexible sheet material comprising a substantially rectangular wall 60 integrally formed with a pair of tongues projecting from its lateral edges and further formed with an upper and a lower tongue integrally projecting from its upper and lower edges, the laterally projecting tongues being bent at their 65 junctures with the first-mentioned wall to form a pair of opposed walls and being further bent toward each other to form members of a fourth wall, the lower tongue being bent at its juncture with the first-mentioned wall to form a bottom 70 for the container and being again bent to extend upwardly to form another member of the fourth wall, whereby the fourth wall is of double thickness, a keeper strap exteriorly extended upon the fourth wall and having end portions extending 75

through the outer members of the fourth wall and bent toward each other between said inner and outer thicknesses, and means for interconnecting said end portions, the upper tongue being bent at its juncture with the first-mentioned wall to form a cover for the container and being further bent to form a flap engageable with said keeper strap.

7. A container formed of flexible sheet material comprising a substantially rectangular wall integrally formed with a pair of tongues projecting from its lateral edges and further formed with an upper and a lower tongue integrally projecting from its upper and lower edges, the laterally projecting tongues being bent at their junctures with the first-mentioned wall to form a pair of opposed walls and being further bent toward each other to form members of a fourth

wall, the lower tongue being bent at its juncture with the first-mentioned wall to form a bottom for the container and being again bent to extend upwardly to form another member of the fourth wall, whereby the fourth wall is of double thickness, a keeper strap exteriorly extended upon the fourth wall and having end portions engaged between the two thicknesses, and a common means for securing the inner and outer thicknesses of the fourth wall to each other and to the end portions of the keeper strap, the upper tongue being bent at its juncture with the first-mentioned wall to form a cover for the container and being further bent to form a flap engageable with said keeper strap. 15
